DESIGN FOR A BROOCH

Frederic Mosell, New York, N. Y.

Application January 21, 1941, Serial No. 98,223

Term of patent 3½ years

To all whom it may concern:

Be it known that I, Frederic Mosell, a citizen of Spain, residing at New York, in the county of New York and State of New York, have invented a new, original, and ornamental Design for a Brooch, of which the following is a specification, reference being had to the accompanying drawing, forming part thereof.

Fig. 1 is a front elevational view of a brooch showing my new design.

Fig. 2 is a side elevational view of Fig. 1 looking from the right hand side.

I claim:

The ornamental design for a brooch, as shown.

FREDERIC MOSELL.
